TOY SWING

Florence Hill, Toronto, Ontario, Canada

Application November 20, 1948, Serial No. 149,739

Term of patent 14 years

(Cl. D34—15)

To all whom it may concern:

Be it known that I, Florence Hill, a citizen of the Dominion of Canada, resident of the city of Toronto, in the Province of Ontario, Dominion of Canada, have invented a new, original, and ornamental Design of a Toy Swing, of which the following is a specification, reference being had to the accompanying drawing, forming part thereof.

Fig. 1 is a side perspective view of a toy swing, showing my new design as it appears with the canopy in raised position; and

Fig. 2 is a fragmentary perspective view showing the upper portion of the swing as it appears with the canopy in lowered position.

I claim:

The ornamental design for a toy swing, as shown.

FLORENCE HILL.
